(57) **CLAIM**

We claim the ornamental design for a pair of shoe soles, as shown and described.

DESCRIPTION

FIG. 1 is a front elevational view of the left component of a pair of shoe soles showing our new design;

FIG. 2 is a rear elevational view thereof.

FIG. 3 is a left side elevational view thereof.

FIG. 4 is a right side elevational view thereof; and,

FIG. 5 is a bottom plan view thereof.

Dot-dashed lines have been used in FIGS. 1, 3, and 4 to show the boundaries of disclaimed portions of the drawings. Dashed lines have been used in FIG. 1 to depict details that are environmental only and form no part of the claimed design.

FIGS. 1–5 depict views of a left shoe sole showing our new design. Respective views of a right shoe sole showing our new design are mirror images of FIGS. 1–5.
